UNITED STATES PATENT OFFICE.

GEORGE BLACKBURN, OF COLUMBUS, ASSIGNOR OF THREE-FOURTHS TO
LEMUEL R. HARTMANN, OF CINCINNATI, OHIO.

BOILER-FURNACE.

SPECIFICATION forming part of Letters Patent No. 258,527, dated May 23, 1882.

Application filed February 23, 1882. (No model.)

To all whom it may concern:

Be it known that I, GEORGE BLACKBURN, of Columbus, Franklin county, Ohio, have invented certain new and useful Improvements 5 in Boiler-Furnaces, of which the following is a specification, reference being had to the accompanying drawings, in which—

Figure 1 is a vertical longitudinal section; Fig. 2, a vertical transverse section at *a b*, and 10 Fig. 3 a vertical transverse section at *c d* and *e f*.

In Fig. 1 the wall *K* is sectional upon the line *g h* of Fig. 3.

The objects of this invention are the economy 15 of fuel and the consumption of smoke.

A is a flue boiler, *B* the smoke-stack, *D* the grate, and *W* the furnace walls and casing, constructed substantially as usual.

U is a wall built in the furnace parallel with 20 the grate, and dividing the furnace into right and left compartments, each of which should have a firing-door. The wall *U* is hollow, the open-topped passage *T* located well toward the front of the grate, and having inlets *T'*, allowing 25 air from the ash-pit to mingle with the hot gases rising from the fires and aiding combustion. The wall *U*, instead of starting from the foundation, as is shown, may start at the grate level if properly supported, and in such case 30 the passage *T* would be a plain vertical one, opening downward into the ash-pit.

Back of the hollow bridge-wall *I* is built an arch, *N*, about as high as the bridge-wall, and having through it the numerous perforations

35 *O*. An air-pipe, *P*, issues at several places in line with the several rows of perforations *O*.

F is the usual passage to the boiler-flues, covered by a flue-plate, *G*. *K* is a dead-wall cutting off the usual communications to passage *F*.

40 At the base of this wall is an arched opening, *M*, whose roof *Y* is best when extended well forward toward the perforated arch *N*. Small top holes, *L*, are made through the wall *K* by leaving out one brick in the locality shown.

45 The gases from the fires, whose current is in some measure maintained close up to the boiler by the arch *N*, impinge against the dead-wall *K*, impelled in this direction by their initial forces and by a slight draft through the open-

ings *L*. On striking the dead-wall *K* the gases 50 rebound and seek their outlet under the arch *M* into the passage *F*. The rebounding action, aided by the arch roof *Y*, causes the reacting current to set well in under the perforated arch *N*, which is thus kept full of gases 55 slightly compressed by the force of the current. Much of this gas mingles with oxygen issuing from pipes *P*, and goes up through the perforations *O* in among the burning gases, just crossing the bridge-wall, where in their 60 revivified condition they are largely consumed. A pipe, *I*, leads from the passage *F*, being connected into the plate *G*, to the interior of the hollow bridge-wall *E*, at *J*. A suction-fan, *I'*, in this pipe draws much of the unconsumed 65 gas from the passage *F*, and before it enters the boiler-flues, and forces it into the hollow bridge-wall. Openings *Q* permit these gases, which become more heated while in the chamber of the hot bridge-wall, to enter the ash-pit 70 and pass directly up through the fire at extreme rear ends of the grate, an air-pipe, *V*, jetting under the openings *Q*, diffusing oxygen among them. A slide, *R*, with an outside handle, serves to regulate or close the openings *Q*. While the fan *I'* is being used the damper *C* should be more or less closed, and when the fan is idle the bridge-wall empty itself of gas and smoke into the stack through pipe *I* and the boiler-flues without passing over 75 the fire, whereby the temperatures may be regulated without extra waste of fuel.

I claim as my invention—

1. The combination of the boiler-furnace, the bridge-wall, the arch *N*, extending rearwardly from the bridge-wall and having parallel rows of perforations *O*, and the jet-pipes *P*, arranged to issue under the arch along said rows of perforations.

2. The combination of the boiler-furnace, 85 the dead-wall *K*, opening *M* under wall *K* *Y*, perforated arch *N*, and air-pipes *P*.

3. The combination of the boiler-furnace, the dead-wall *K*, opening *M* thereunder, roof *Y*, extending forward therefrom, and perforated 95 arch *N*, with air-pipes *P*.

4. The combination of the boiler-furnace, perforated arch *N*, air-pipes *P*, dead-wall *K*,

opening M thereunder, and top openings, L, in said dead-wall.

5. The combination of the boiler-furnace, perforated arch N, air-pipe P, dead-wall K, opening M, top openings, L, and roof Y.
6. The combination of the boiler-furnace, the hollow bridge-wall E, slitted openings Q

in the front of the bridge-wall, jetted pipe V below the openings Q, fan I', and pipe H.

GEO. BLACKBURN.
